BASE SUPPORT UNIT FOR A TENTERING MACHINE

Frederick Hyatt, Providence, R.I., assignor to Bevis Industries, Inc., Providence, R.I.

Filed May 27, 1968, Ser. No. 12,083

Term of patent 14 years

Int. Cl. D15—06

U.S. Cl. D92—15

FIG. 1

FIG. 2

FIG. 3

FIG. 4

FIG. 5

FIG. 6

FIG. 1 is a perspective view of a base support unit for a tentering machine, showing my new design:

FIG. 2 is a top plan view, thereof;

FIG. 3 is a left end elevational view, thereof;

FIG. 4 is a right side elevational view, thereof, the left side being a mirror image of the side shown;

FIG. 5 is a right end elevational view, thereof; and

FIG. 6 is a bottom plan view thereof.

I claim:

The ornamental design for a base support unit for a tentering machine, as shown and described.
